Application November 3, 1950, Serial No. 193,845

19 Claims. (Cl. 178—44)

1

This invention relates to wave transmission and more particularly to frequency discriminators.

An object of the invention is to provide two transmission paths in which the difference between the phase shifts therein will be constant over a range of frequencies.

Another object is to produce a unidirectional output voltage which is proportional to, and the sign of which is determined by, the deviation of an alternating input voltage from a reference frequency.

Other objects are to simplify the construction and operation, decrease the cost, and improve the performance of frequency discriminators.

A more specific object is to provide a frequency discriminator which will maintain high discrimination over a range of frequencies without requiring the adjustment of an associated phase shifter.

As an example of the application of the invention, there is disclosed a frequency discriminator comprising two transmission paths connected at their input ends, a hybrid junction having a pair of conjugate points to which the other ends of the paths are respectively connected, and, associated with one of the paths, an adjustable impedance resonant at the input frequency. The two paths, which may be constituted by wave guides, have lengths and cut-off wavelengths so chosen that the phase shifts in the two paths differ by a substantially constant amount equal to an odd integral multiple of $\pi/2$ radians over a considerable range of frequencies. The two guides will, in general, differ in length, in velocity of propagation, and in at least one cross-sectional dimension. With this construction the discrimination is maintained at a high value over the entire operating frequency range.

It has been customary heretofore to use in both paths wave guides which have the same cross section and the same velocity of propagation. When this is done, however, the phase shifts in the two paths will no longer have the required difference if the input frequency is changed. This is owing to the fact that the difference in the lengths of the two paths no longer represents the same fraction of a wavelength. An additional change in phase shift results from the change in velocity of propagation in wave guides with frequency. Therefore, in microwave frequency discriminators constructed in this way it is necessary, if high discrimination is to be maintained, to provide an adjustable phase shifter in one or both of the paths for maintaining the required phase difference when the input frequency is varied.

In the frequency discriminator disclosed herein the need for adjustable auxiliary phase shifters is entirely eliminated. Since one or more adjustable

elements may thus be omitted, the construction of the device is simplified and the cost thereby reduced. Furthermore, the device is easier to operate and its performance is improved because it is unnecessary to adjust one or more auxiliary phase shifters whenever the input frequency is changed.

The nature of the invention will be more fully understood from the following detailed description and by reference to the accompanying drawing, the single figure of which shows, by way of example only, a perspective view, partly cut away and schematic in part, of one embodiment of a frequency discriminator embodying the invention.

As shown, the frequency discriminator comprises two transmission paths 2 and 3 connected at their input ends, a hybrid wave-guide junction 4 having a pair of conjugate points to which the other ends of the paths 2 and 3 are respectively connected, and an adjustable impedance 5 associated with the path 2. Each of the paths 2 and 3 is constituted by a wave guide of the hollow-pipe type having a rectangular cross section. As explained more fully below, the lengths and cut-off wavelengths of the guides 2 and 3 are so proportioned that their respective phase shifts differ by substantially $\pi/2$ radians, or an odd integral multiple thereof, at the operating frequency f_0 and over a considerable range of frequencies on each side thereof.

As indicated by the arrow 7, electromagnetic wave energy of the mid-band operating frequency f_0 from a suitable source, not shown, is fed in through the wave guide 8, which is a continuation of the guide 2. In the present example the operating mode is the dominant transverse electric mode, usually designated TE_{10} . This mode is chosen because, for a given frequency f_0 , it may be transmitted in a wave guide of minimum cross section. The electric field is polarized in a direction perpendicular to the wider sides of the guide, as shown by the vector E_x . Part of the input energy is fed into the end of the guide 3 through a circular orifice 9 in one of the wider sides of the guide 8.

The adjustable impedance 5 comprises a cylindrical cavity resonator 10 which is inserted between two portions of the guide 2 and coupled thereto by means of the oppositely disposed circular orifices 12 and 13. In order to provide maximum sensitivity of frequency discrimination the areas of the orifices 9, 12 and 13 are so chosen that substantially equal amounts of energy are supplied to the hybrid junction 4 over the paths 2 and 3. The resonator 10 is tuned to resonate at the operating frequency f_0 by an axial adjustment of the push rod 14, to the end of which is secured a reflecting piston 15.

The hybrid junction 4 comprises two tandem-connected and axially-aligned sections of rectangular wave guide 17 and 18 of substantially equal lengths, each closed at its outer end by a reflecting plate 19. The other ends of the guides 2 and 3 are connected to the hybrid junction 4 at its center in such a way that, at the point of junction, the longitudinal axes of the guides 2, 3 and 17-18 are mutually perpendicular. The longitudinal axes of the guides 2 and 17-18 lie in a plane perpendicular to the electric field vectors E_1 and E_2 in the guides 2 and 17-18, and these axes of the guides 3 and 17-18 lie in a plane parallel with the vectors E_1 and E_2 in the guides 3 and 17-18. The guide 2 is connected to one of the narrower sides of the guide 17-18, and the guide 3 to one of the wider sides. Portions of the side walls of the guide 17-18 are removed to permit the energy from the guides 2 and 3 to enter. A post 23 mounted on the inside of the lower wall of the guide 17-18 at its center and extending into the end of the guide 3 and a transversely disposed plate 24 mounted on one of the narrower walls of the guide 3 near the end thereof and extending part-way across the guide provide impedance matching between the hybrid junction 4 and the guides 2 and 3 in accordance with well-known methods such as are described in the book "Microwave Duplexers" edited by Smullin and Montgomery and published in 1948 by the McGraw-Hill Book Company, New York. The theory and construction of hybrid junctions for wave guides are discussed in greater detail in United States Patent No. 2,445,896 to W. A. Tyrrell, issued July 27, 1948.

The wave energy in the guides 17 and 18 is rectified by means of the crystal detectors 25 and 26, respectively, which are mounted within the guides near the outer ends thereof at a proper distance from the reflecting plate 19 to provide an effective impedance match and are poled to provide output voltages of opposite polarity. A wire lead 28 is connected to the detector through a by-pass condenser comprising a grounded cylindrical outer electrode 29 and a concentric cylindrical inner electrode 30 conductively connected to the lead 28. The electrodes 29 and 30 are separated by a dielectric, which may be air.

The leads 28 are connected through two substantially equal series-connected resistances 31 and 32 which are connected at their junction to an output terminal 34. The other output terminal 35 is connected to a point 36 on one of the guides 17 and 18 and is grounded as shown at 37. A load 38 of suitable impedance is shown connected to the output terminals 34 and 35.

The operation of the frequency discriminator may be described as follows: The input energy divides into two equal portions which are transmitted along the paths 2 and 3, respectively, and impressed upon conjugate points of the hybrid junction 4 in phase quadrature when the resonator 5 is tuned to the operating frequency f_0 . The portion of the energy entering the junction 4 from the path 2 again divides into equal portions which flow in the arms 17 and 18, respectively, in phase with the energy in the path 2. The portion of energy entering the junction 4 from the path 3 also divides into equal portions which flow in the arms 17 and 18, respectively. If we consider the energy in the arm 17 from the path 3 to be in phase with the energy in the path 3, then the energy in the arm 75

18 from the path 3 is in phase opposition with the energy in the path 3. When it is tuned to the operating frequency f_0 , the resonator 10 introduces no phase shift in the path 2, and the relative phase shift between the energy entering the junction 4 from the path 2 and that entering from the path 3 will be $\pi/2$ radians, or an odd multiple thereof. In each of the arms 17 and 18 the energy from the path 2 will thus be in quadrature with an equal amount of energy from the path 3. The unidirectional output voltages from the detectors 25 and 26 are proportional to the vector sums of the energy in the arms 17 and 18, respectively, but these voltages are of opposite sign with respect to the ground 37. Therefore, under these circumstances, equal and opposite voltages will appear between the output terminals 34 and 35. If the load 38 is a voltmeter, or other indicating device, it will show a zero reading.

Now if either the input frequency f_0 or the resonant frequency f_r of the resonator 10 is changed, these frequencies will no longer coincide, and the resonator will introduce into the path 2 a phase shift which, near resonance, is proportional in magnitude to the difference between f_0 and f_r , and the sign of which depends upon whether f_0 or f_r is higher. The quadrature relationship in the arms 17 and 18 with respect to the energy from the paths 2 and 3 is thus upset. In one arm the angle between the two components becomes acute and the vector sum is increased, while in the other arm the angle becomes obtuse and the vector sum is decreased. As a result, the output voltage from one of the detectors 25 and 26 increases, while that from the other decreases, providing a net positive or negative voltage at the output terminals 34 and 35. For small deviations this voltage will be substantially proportional to the difference between f_0 and f_r , and its polarity with respect to the ground 37 will depend on whether f_0 is higher or lower than f_r .

A frequency discriminator is sometimes required to operate over a band of frequencies. When the operating frequency f_0 is changed to some new frequency f_0' , the resonator 10 is returned to resonate at f_0' . But the output voltage at the terminals 34 and 35 will be zero for an input frequency f_0' only if the paths 2 and 3 have a phase difference of $\pi/2$, or an odd integral multiple thereof, at the new frequency. Heretofore, the required phase relationship has been maintained by providing an adjustable phase shifter in one or both of the paths 2 and 3 and adjusting them as f_0 is changed. In accordance with the present invention, however, the lengths and cut-off wavelengths of the two paths 2 and 3 are chosen, as explained below, so that the required phase difference is substantially maintained over a considerable frequency range without resorting to auxiliary phase shifters.

If S_1 and S_2 are the lengths, respectively, of the two transmission paths and their cut-off wavelengths in free space are λ_1 and λ_2 , respectively, their phase difference θ in radians at the free-space wavelength λ , corresponding to any frequency f , is given by the expression

$$\theta = \frac{2\pi}{\lambda} \left[\frac{S_1}{\lambda_1} \sqrt{\lambda_1^2 - \lambda^2} - \frac{S_2}{\lambda_2} \sqrt{\lambda_2^2 - \lambda^2} \right] \quad (1)$$

where

$$\lambda = \frac{\lambda_1 \lambda_2}{\lambda_1 + \lambda_2} \quad (2)$$

The first derivative of expression (1) with respect to λ gives the slope of the θ versus λ characteristic. For the least change of θ over the operating frequency range, this slope is made zero at the mid-band operating free-space wavelength λ_0 by setting this derivative equal to zero and substituting λ_0 for λ . This gives the following required relationship between S_1 and S_2 .

$$\frac{S_1}{\sqrt{\lambda_1^2 - \lambda_0^2}} = \frac{rS_2}{\sqrt{r^2\lambda_1^2 - \lambda_0^2}} \quad (3)$$

From Equations 1 and 3 the required lengths of the two paths are found to be

$$S_1 = \frac{r^2\lambda_1\theta\sqrt{\lambda_1^2 - \lambda_0^2}}{2\pi(1-r^2)\lambda_0} \quad (4)$$

and

$$S_2 = \frac{r\lambda_1\theta\sqrt{r^2\lambda_1^2 - \lambda_0^2}}{2\pi(1-r^2)\lambda_0} \quad (5)$$

Computations have shown that the change in θ with frequency is minimized if the longer path has the longer cut-off wavelength. Thus, if S_1 is longer than S_2 , then λ_1 should be greater than λ_2 . As will be shown later, this means that the longer wave guide should be wider than the shorter wave guide.

Equations 4 and 5 give the required lengths S_1 and S_2 , in terms of their cut-off wavelengths λ_1 and λ_2 , of two sections of wave guide in which the phase difference θ will remain most nearly constant over the widest possible frequency range centered at f_0 . Such a pair of wave guides find useful application in a number of transmission devices. When used as the paths 2 and 3 in a frequency discriminator of the type described above, θ is usually chosen as an odd integral multiple of $\pi/2$ radians. When this multiple is chosen as unity, Equations 4 and 5 become

$$S_1 = \frac{r^2\lambda_1\sqrt{\lambda_1^2 - \lambda_0^2}}{4(1-r^2)\lambda_0} \quad (6)$$

and

$$S_2 = \frac{r\lambda_1\sqrt{r^2\lambda_1^2 - \lambda_0^2}}{4(1-r^2)\lambda_0} \quad (7)$$

If the cut-off free-space wavelength λ_c of a rectangular wave guide is known, its inside width a and height b may readily be found from the formula

$$\lambda_c = \frac{2}{\sqrt{\left(\frac{m}{a}\right)^2 + \left(\frac{n}{b}\right)^2}} \quad (8)$$

where m denotes the number of half period variations in the field in the direction of the width a and n denotes the number of half period variations in the field in the direction of the height b . For example, if the fundamental transverse electric mode, TE_{10} , is used, m is unity and n is zero, and Formula 8 reduces to

$$\lambda_c = 2a \quad (9)$$

from which

$$a = \frac{\lambda_c}{2} \quad (10)$$

The height b determines the characteristic impedance of the wave guide and is selected to provide the desired impedance. However, if it is desired to prevent the transmission of a higher order mode, there is a maximum permissible height b . For example, if transmission of the TE_{11} or TE_{01} mode is to be prevented, this height cannot exceed a half wavelength in free space at the upper end of the operating frequency band. 75

In the phase discriminator disclosed herein either the path 2 or the path 3 may be the longer. As shown, the path 2 is the longer. The length S_1 of the path 2 is found by adding the distance measured along the longitudinal axis of the guide 2 from the center of the orifice 9 to the orifice 12 and the distance between the orifice 13 and the point where the path joins the hybrid junction 4. The resonator 10 introduces no phase shift at resonance, and therefore its diameter is not included in measuring the length of the path 2. The length S_2 of the path 3 is measured along the longitudinal axis of the guide from the orifice 9 to the point where the guide joins the junction 4.

Before the lengths S_1 and S_2 can be found it is necessary to choose the corresponding cut-off wavelengths λ_1 and λ_2 . A recommended design procedure is to choose λ_2 sufficiently long to permit the transmission of the lowest frequency in the desired operating range and λ_1 as long as possible without permitting the transmission of an undesired mode or modes of a higher order than the mode to be utilized. It has been found that making λ_1 and λ_2 as long as possible minimizes the deviation of θ from the desired value as the operating frequency f_0 is changed. When λ_1 and λ_2 have been selected, the lengths S_1 and S_2 are found from Formulas 4 and 5, respectively, or, for a phase difference of $\pi/2$, from Formulas 6 and 7, respectively.

In determining the value of the phase difference θ to be used in Formulas 4 and 5 allowance must be made for the phase shifts that may be introduced by any impedance matching devices, such, for example, as the post 23 and the plate 24. Thus if θ_2 is the sum of the phase shifts added by such devices in the path 2 and θ_3 is the total phase shift added to the path 3, the proper value of the phase difference θ' to be substituted for θ in Formulas 4 and 5 is given by

$$\theta' = \theta + \theta_3 - \theta_2 \quad (11)$$

As an example, if the discriminator shown is to operate over a band of frequencies with a mid-band frequency f_0 of 9030 megacycles, corresponding to a mid-band wavelength λ_2 of 3.33 centimeters, and utilize the TE_{10} mode, the wave guide 2 may have a length S_1 of 13.822 centimeters and a width of 3.102 centimeters, giving a cut-off wavelength λ_1 of 6.204 centimeters, and the wave guide 3 may have a length S_2 of 13.320 centimeters and a width of 2.860 centimeters, corresponding to a cut-off wavelength λ_2 of 5.720 centimeters. With these dimensions the total variation in the phase difference θ will not exceed 0.34 degree over a 12 per cent frequency band. With such a small variation, no auxiliary phase shifters are required to obtain high discrimination throughout the band. As a comparison, if the wave guides 2 and 3 are made of the same width 2.860 centimeters, in accordance with prior practice, the corresponding variation in θ over the same band will be more than 16 degrees, requiring the addition of one or more variable phase shifters to obtain a satisfactorily high discrimination.

What is claimed is:

1. In combination, two transmission paths having lengths S_1 and S_2 , respectively, and cut-off wavelengths λ_1 and λ_2 , respectively, so proportioned that the difference θ between the phase shifts therein is substantially constant over a considerable range of frequencies, an adjustable

resonant impedance associated with one of said paths, and a hybrid junction having a pair of conjugate points, said paths being connected together at one end and to said points, respectively, at their other ends.

2. The combination in accordance with claim 1 in which said lengths are approximately determined, respectively, by the formulas

$$S_1 = \frac{r^2 \lambda_1 \theta \sqrt{\lambda_1^2 - \lambda_0^2}}{2\pi(1-r^2)\lambda_0}$$

$$S_2 = \frac{r \lambda_1 \theta \sqrt{r^2 \lambda_1^2 - \lambda_0^2}}{2\pi(1-r^2)\lambda_0}$$

where r is the ratio of λ_2 to λ_1 , and λ_0 is the wavelength at the mid-band frequency of said range.

3. The combination in accordance with claim 2 in which each of said paths comprises a wave guide.

4. The combination in accordance with claim 3 in which said wave guides are rectangular in cross section and the longer of said guides has the greater width.

5. The combination in accordance with claim 1 in which the longer of said paths has the longer cut-off wavelength.

6. The combination in accordance with claim 1 in which λ_1 is made as long as possible without permitting the transmission of an undesired mode of a higher order than the mode to be utilized, and λ_2 is long enough to permit the transmission of the lowest frequency in said range.

7. A frequency discriminator comprising two transmission paths connected at their input ends, a hybrid junction having a pair of conjugate points to which the other ends of said paths are respectively connected, and an adjustable resonant impedance associated with one of said paths, said paths having lengths S_1 and S_2 , respectively, and cut-off wavelengths λ_1 and λ_2 , respectively, so proportioned that the difference θ between the phase shifts therein is substantially equal to an odd integral multiple of $\pi/2$ over a considerable frequency range.

8. A frequency discriminator in accordance with claim 7 in which said lengths are approximately determined, respectively, by the formulas

$$S_1 = \frac{r^2 \lambda_1 \theta \sqrt{\lambda_1^2 - \lambda_0^2}}{2\pi(1-r^2)\lambda_0}$$

$$S_2 = \frac{r \lambda_1 \theta \sqrt{r^2 \lambda_1^2 - \lambda_0^2}}{2\pi(1-r^2)\lambda_0}$$

where r is the ratio of λ_2 to λ_1 and λ_0 is the wavelength at the mid-band frequency of said range.

9. A frequency discriminator in accordance with claim 7 in which each of said paths comprises a wave guide.

10. A frequency discriminator in accordance with claim 9 in which said wave guides are rectangular in cross section and the longer of said guides has the greater width.

11. A frequency discriminator in accordance with claim 7 in which the longer of said paths has the longer cut-off wavelength.

12. A frequency discriminator in accordance with claim 7 in which λ_1 is made as long as possible without permitting the transmission of an undesired mode of a higher order than the mode to be utilized, and λ_2 is long enough to permit the transmission of the lowest frequency in said range.

13. A frequency discriminator in accordance with claim 7 in which said paths are adapted to convey substantially equal amounts of microwave energy to said hybrid junction.

14. A frequency discriminator in accordance with claim 7 which includes means for matching impedances between said hybrid junction and said paths.

15. A frequency discriminator operable over a considerable range of frequencies comprising two wave guides of the hollow-pipe type connected at their input ends, a hybrid junction having a pair of conjugate points to which the other ends of said guides are respectively connected, and an adjustable cavity resonator coupled to one of said guides, said guides having different lengths S_1 and S_2 , respectively, and different cut-off wavelengths λ_1 and λ_2 , respectively, which approximately satisfy the relationships

$$S_1 = \frac{r^2 \lambda_1 \theta \sqrt{\lambda_1^2 - \lambda_0^2}}{2\pi(1-r^2)\lambda_0}$$

$$S_2 = \frac{r \lambda_1 \theta \sqrt{r^2 \lambda_1^2 - \lambda_0^2}}{2\pi(1-r^2)\lambda_0}$$

where r is the ratio of λ_2 to λ_1 , λ_0 is the wavelength at the midband frequency of said range, and θ is equal to an odd integral multiple of $\pi/2$.

16. A frequency discriminator in accordance with claim 15 in which the longer of said paths has the longer cut-off wavelength.

17. A frequency discriminator in accordance with claim 15 in which said wave guides are rectangular in cross section and the longer of said guides has the greater width.

18. A frequency discriminator in accordance with claim 15 in which said multiple is unity.

19. A frequency discriminator in accordance with claim 15 which is adapted to operate in the dominant transverse electric mode.
